UNITED STATES PATENT OFFICE.

CHARLES G. BOECK, OF JACKSON, MICHIGAN, ASSIGNOR TO NOVELTY MANUFACTURING CO., OF JACKSON, MICHIGAN, A CORPORATION OF MICHIGAN.

AUTOMOBILE-MUFFLER.

1,002,801.

Specification of Letters Patent. Patented Sept. 5, 1911.

Application filed February 2, 1911. Serial No. 606,232.

To all whom it may concern:

Be it known that I, CHARLES G. BOECK, a citizen of the United States, residing at Jackson, in the county of Jackson and State 5 of Michigan, have invented certain new and useful improvements in Automobile-Mufflers, of which the following is a specification.

This invention relates to improvements in 10 mufflers for explosive engines, and has especial reference to mufflers employed on motor vehicles.

The object of the invention is to provide a muffler of compact form and simple construction which may be readily attached to 15 or detached from any automobile or other motor vehicle and by the use of which the noise attendant upon the exhaust of explosive engines will be overcome and the back 20 pressure upon the engine reduced to a minimum.

The invention also seeks to provide a construction of such character that the weight 25 of the entire muffler will be inconsiderable and consequently the dead weight of the vehicle appreciably reduced, so that the load placed upon the engine will be minimized.

These stated objects, and such other incidental objects as will hereinafter appear, 30 are attained by the use of the device illustrated in the accompanying drawings, and the invention consists in certain novel features which will be first fully described and then more particularly pointed out in the 35 appended claims.

In the drawings, Figure 1 is a view of a 40 form of muffler embodying my improvements showing the same partly in side elevation and partly in longitudinal vertical section; Fig. 2 is a transverse section taken on the line 2—2 of Fig. 1; Fig. 3 is a longitudinal vertical section of a portion of the muffler taken at right angles to the plane of the section shown in Fig. 1; Fig. 4 is a detail 45 perspective view of one of the baffle plates; Fig. 5 is a plan view of a blank showing a modified construction; Fig. 6 is a detail perspective view of a portion of the baffle member constructed from the blank 50 shown in Fig. 5.

The casing 1 of my improved muffler may be straight, as illustrated, or of a sinuous form, and is a tube of such a diameter as will permit one end to fit closely over the

end of the exhaust pipe, indicated at 2. 55 Upon the said end of the casing 1, I provide rigid brackets 3 through which a securing bolt 4 is inserted to firmly clamp the end of the casing around the end of the exhaust pipe. 60

Adjacent the inlet end of the casing, by which term is meant the end clamped upon the exhaust pipe, I provide upon the casing a cut-out 5, in order that gases from the engine or motor may be discharged without 65 passing through the muffler. This cut-out consists of a disk or valve loosely mounted upon the end of a lever 6, which is fulcrumed between its ends upon a bracket 7 secured rigidly to and projecting laterally 70 from the casing, and to the outer end of the lever I connect a link or rod 8 which extends up within the body of the vehicle, to a point where it may be conveniently operated by the chauffeur. 75

It will be observed that the cut-out is mounted directly upon the casing of the muffler so that no particular construction of exhaust pipe is necessary and no peculiar fitting is needed when attaching the muffler 80 to any automobile now in use.

Within the casing 1, I provide a series of baffle plates 9, which, in the construction shown in Figs. 1 to 4, are secured rigidly to bars or strips 10 extending longitudinally 85 of the casing from a point adjacent the cut-out to the rear or discharge end thereof, as clearly shown in Fig. 1. These bars or strips 10 are detachably secured within the casing by bolts or rivets 11, inserted 90 through suitable openings in the walls of the casing and the bars, as shown, and the baffle plates are formed with tongues 12 which lie against the said strips or bars, and are riveted or otherwise securely fastened thereto, it being understood, however, that the baffles and base bars may be cast in one piece. The baffle plates extend from the tongues 12 toward and slightly beyond the longitudinal axis of the casing, and their 100 side edges diverge from the tongue, as shown most clearly in Figs. 1 and 4, the plates being rolled or otherwise given an arcuate form, illustrated most clearly in Fig. 3. The baffles are so arranged within 105 the casing that their concave faces will be presented to the inlet end of the casing, and, consequently, the gases passing from the ex-

haust pipe to the muffler will be caught by the baffle plates and given a reverse rolling action, so that their passage through the casing will be effectually retarded in order 5 that their force may be spent before they reach the discharge end of the casing. It will also be noted, upon reference to Fig. 3, that the free edges of the baffle plates extend slightly past the axial center of the tubular casing, and that the alternate baffles 10 extend inwardly from opposite sides of the casing, as a result of which arrangement the gases are not only given a reverse rolling action in their effort to escape from the muffler, but are also thrown alternately 15 against the opposite sides of the muffler and consequently are given a tortuous circulation therethrough. As a result of this tortuous circulation and rolling motion of 20 the exhaust gases, they will be expanded and their force spent before the rear end of the muffler casing is reached, so that their final exit whether through the end of the tube, as in Fig. 3, or through the discharge 25 openings 12', as in Fig. 1, is unaccompanied by any harsh sound. The side edges of the baffle plates not only diverge from the base, but are also given a curved form, so that 30 they will fit snugly against the walls of the casing, as shown most clearly in Fig. 2, and, consequently, there is no clear passage 35 through the tube to permit the direct escape of the exhaust gases.

It will be readily noted from the drawings, taken in connection with the foregoing 35 description, that I have provided two mating members each consisting of a base in the form of a narrow strip or bar adapted to extend longitudinally of the casing and 40 a plurality of baffle plates projecting from the strip or bar and given a concavo-convex formation so as to arrest the escaping gases and deflect the same from side to side of the casing, and also throw them 45 back upon themselves so as to entirely eliminate their offensive qualities. The construction of the parts is such that they may be all made from sheet metal, and, consequently, will add no appreciable weight to 50 the vehicle to which the device may be attached. The bases or strips 10 and the baffle plates attached thereto may be removed bodily from the casing or inserted 55 thereinto by merely sliding the same longitudinally, as will be readily understood, so that the breakage of a single baffle plate or of either base or holding bar does not entail the provision of an entirely new muffler. Furthermore, this construction facilitates 60 the manufacture of the device and keeps the cost at a low figure.

In Figs. 5 and 6 I have illustrated a construction which may be preferred to that previously described and illustrated in 65 the other figures, in which I take a sheet

metal blank 13 and form slits 14 therein consisting of a transverse straight portion 15 and curved portions 16 extending from the ends of the said transverse portion and converging toward the longitudinal center 70 of the blank. The portion 17 of the blank defined by this slit is then struck up and rolled by means of suitable dies so as to be given the shape of the baffle plates shown in the other figures, and the blank is then 75 rolled upon its own longitudinal center, so as to be given a trough-like form, as shown in Fig. 6. This particular form of baffle and support produces an integral structure which may be inserted or withdrawn in the 80 same manner as the structure shown in the other figures, and may be more rapidly and cheaply produced.

The operation of my device and the many 85 advantages to be derived from its use are thought to be evident from the foregoing description, taken in connection with the accompanying drawings, without further detailed mention of the same.

I claim as my invention and desire to 90 secure by Letters Patent:

1. A muffler comprising a tube having an open end adapted to be secured on the end of an exhaust pipe, and a plurality of imperforate baffle plates detachably secured to the inner walls of the tube at diametrically opposite points of the same and alternately arranged to project beyond the longitudinal axis of the tube. 95

2. A muffler consisting of a tubular casing, and imperforate baffle plates secured alternately at diametrically opposite points of the casing, said baffle plates having their edges fitting closely to the walls of the casing and their inner ends extending past 100 the longitudinal center of the casing. 105

3. A muffler consisting of a tubular casing, and pairs of baffle members detachably secured therein at diametrically opposite points thereof and each comprising a longitudinal base and arcuate baffles carried by 110 said base.

4. The combination with a muffler casing, of a series of baffle plates arranged therein and having a concavo-convex form, the 115 concave faces of the baffles being arranged toward the inlet end of the casing and the baffles projecting alternately from the opposite sides of the casing with their free edges extending past the axial center of the 120 casing.

5. A baffle member for use in mufflers comprising a base, and a plurality of imperforate curved baffle plates carried by and projecting at intervals from the base and 125 arranged transversely thereto.

6. A muffler comprising a tubular casing, a base extending longitudinally of the casing and detachably secured therein, and a plurality of imperforate baffle plates carried 130

by said base and disposed transversely thereto.

7. A muffler consisting of an open-ended tubular casing, and mating diametrically 5 opposite baffle members secured therein and removable bodily endwise through the open end of the casing, each of said members consisting of a base adapted to extend longitudinally of the casing against the wall of the same, and a plurality of concavo-convex 10 imperforate baffles projecting from the base, the height of the baffles being more than one-half the diameter of the casing and the

edges of the baffles being arcuate to fit closely against the casing.

8. A baffle member for use in mufflers comprising a base, and a plurality of imperforate curved baffle plates integral with the base and arranged transversely thereto.

In testimony whereof I affix my signature, 20
in presence of two witnesses.

CHARLES G. BOECK.
